PRODUCTION OF SOLVENTS

Jacquelin E. Harvey, Jr., Atlanta, Ga., assignor
of one-half to Southern Wood Preserving Com-
pany, East Point, Ga., a corporation of Georgia

Application March 14, 1941, Serial No. 383,460

5 Claims. (Cl. 196—53)

The present invention relates to the production of valuable liquids from tars of aromatic content and fractions thereof, crude and/or refined.

This application is a continuation in part of my application Ser. No. 352,672, filed August 14, 1940, for Production of solvents, copending here-with, as to all matter common to the two applications.

An object of the present invention is the sub-
jection of tars of aromatic content and fractions thereof, crude and/or refined, to the action of hydrogen in step-wise manner, whereby to pro-
vide solvents of increased solvency, said solvents being characterized, when compared to the im-
mediate starting material, by a fractional incre-
ment in the low boiling range in excess of frac-
tional increment in the higher boiling range.

A further object of the present invention is the production of refined solvents of lowered corrosivity and superior solvency, the characteristics of which are, among other things, dependent upon hydrogen supply as hereafter explained.

Starting materials of the present process in-
clude tars and fractions thereof of aromatic con-
tent characterized by content of oxygenated com-
pounds and sulphur, said tars being derived from
coal, petroleum, or gas or gases containing car-
bon; as for instance coke oven tar, water gas
tar, gas house tar and tars of aromatic content
in general; tars produced by cracking hydro-
carbons; tars resulting from the action of hydro-
gen on hydrocarbons; high boiling extractions
of carbonaceous substances; high boiling hydro-
carbons of aromatic content having olefinic
and/or naphthenic content.

Starting materials of the present process also include tars of aromatic content from which low boiling fractions have been removed, as for in-
stance tars from which solvent oils have been removed. Viewed broadly, the starting materials of the present process are tars of aromatic content, fractions of said tar more viscous than the starting material due to removal of low boiling fractions from the starting material, high boil-
ing fractions and pitches. Materials previously subjected to the action of hydrogen are suitable starting materials.

Especially attractive as starting materials are the tars from high temperature coke ovens which are available in large quantities at low prices.

The present invention may be viewed broadly as a process for the production of refined solvents of lowered corrosivity by subjecting the starting material in step-wise manner to the controlled

action of hydrogen whereby to produce said solvent having enhanced solvency, and as com-
pared to the immediate parent material, an in-
crement of fractions in the lower boiling range
5 in excess of fractional increment in the higher
boiling range.

The following examples will serve to illustrate the general principle upon which the practice of the present invention is based, as well as the process of the present invention.

The invention will be understood from the following description of illustrative steps comprising various methods of securing the objects of the invention, when read in connection with 15 the accompanying drawing wherein the figure is a diagrammatic sketch of an apparatus for carrying out a form of the process of the invention and wherein the nature of the step carried out in each chamber and the contents there-
20 of are indicated by legend.

Example 1.—A sulphur bearing coal tar creosote, characterized by content of oxygenated com-
pounds, a coke residue in excess of 1%, a spe-
cific gravity of in the order of 1.06, and substan-
tially 25% residue above 355° C., is subjected to
25 the action of hydrogen at 395° C. and 200 atmos-
pheres pressure whereby to lower sulphur con-
tent thereby lowering corrosivity, at least pro-
viding for lowered corrosivity in the finished ma-
terial as hereinafter explained. The material of
30 lowered sulphur content is then passed through
a high pressure reaction vessel while simulta-
neously flowing hydrogen therewith in the pres-
ence of molybdenum oxide catalyst and a ma-
terial adapted to influence the decomposition of
35 oxygenated compounds contained in the starting
material, as for instance iodine, at a tempera-
ture of 430° C. and 300 atmospheres pressure. The
time of contact is one hour and the flow of
40 gas 15,000 cubic feet per barrel refined creosote.
The beneficiated creosote upon inspection will
be found to have a lowered coke residue, boiling
range, specific gravity, viscosity and oxygen con-
tent. Solvency in some of the lower fractions
45 will be lowered as compared to solvents extant
of comparable boiling range.

The lowering of oxygen content will flow from, among other things, the effect of the presence of a material selected from the group consisting of halogens, halids and derivatives thereof. By the presence of said material the reaction in the hydrogen step noted is enhanced.

By the higher boiling range is meant, as an example, the upper half of the boiling range.

Solvents in some of the lower fractions of the

beneficiated creosote will be reduced in quality as compared to solvents extant of comparable boiling range.

The beneficiated creosote is stripped to an upper limit of 300° C. and at least a portion of the low boiling fractions thereof are passed through a high pressure reactor at 525° C. and 200 atmospheres pressure while contacting a molybdenum oxide catalyst. The flow of hydrogen is so controlled as to induce a solvent having increased solvency and an increment of fractions in the lower boiling range in excess of fractional increment in the higher boiling range.

The solvent so produced may be fractionated to provide a refined solvent of lowered corrosivity of any boiling range within the limits of the immediate parent material, as for instance:

	°C.
Benzol	78-120
Toluol	100-150
Hi-flash naphtha	150-200
Heavy naphtha	150-290
Plasticizers	160-360

or others.

The refined solvents may serve as substitutes for the material having the boiling range or ranges of the commercial solvents noted above.

In the foregoing example it will be noted that the present process provides a method for contacting the starting material with hydrogen whereby to lower sulphur content, thereafter, contacting the material of lowered sulphur content with hydrogen whereby to produce an intermediate product of lowered solvency, specific gravity, boiling range, coke residue, and viscosity; stripping from the beneficiated material a low boiling fraction thereof and subjecting at least a portion of said low ends to the controlled action of hydrogen whereby to enhance solvency and produce, as compared to the immediate starting material, an increment of fractions in the lower boiling range in excess of fractional increment in the higher boiling range, thus providing the refined solvent of lowered corrosivity of the present process.

Looked at in one manner the present process provides a method for treating tars of aromatic content, and fractions thereof, with hydrogen in step-wise manner whereby to provide refined solvents of lowered corrosivity, said solvents being characterized by increased solvency as compared to their immediate starting material as heretofore disclosed. The step-wise action of hydrogen being further characterized by providing hydrogen in flow that depolymerizes ring multiplicities thereby inducing lowered specific gravity, coke residue, boiling range, solvency and viscosity, and last, by providing hydrogen in flow that, among other things, increases solvency.

The step-wise action of hydrogen thus provides a method for securing refined solvents of lowered corrosivity and superior solvency from high boiling hydrocarbons of aromatic content, said high boilers characterized by the presence of ring multiplicities of great thermal susceptibility.

Example 2.—A sulphur containing coal tar, specific gravity 1.1641, a coke residue in excess of 1%, and in excess of 35% boiling at 355° C., and further characterized by content of oxygenated compounds is subjected to the action of hydrogen at 330° C. and 300 atmospheres pressure for such a length of time as to lower sulphur content. The coal tar of lowered sulphur content is then passed through a high pressure re-

action vessel while simultaneously flowing hydrogen therewith at a pressure of 300 atmospheres and a temperature of 410° C.; time of contact one hour, catalyst vanadium oxide and a material selected from the group consisting of halogens, halids, and derivatives thereof including substitution and addition products thereof, and flow of hydrogen 15,000 cubic feet per barrel feed stock. The thus treated coal tar is found to have a lowered specific gravity, viscosity, coke residue, boiling range, and oxygen content. In some of the fractional parts of the treated coal tar there will be lowered solvency as compared to solvents extant of comparable boiling range.

15 The beneficiated tar is then stripped to an upper limit of 360° C. and the low ends thereof subjected to the action of flow of hydrogen at 490° C. and 200 atmospheres pressure and for such a length of time as to increase solvency and produce an increment of fractions in the lower boiling range in excess of fractional increment in the higher boiling range, thus providing the refined solvent of the present process.

Example 3.—A high boiling fraction of coal tar characterized by sulphur content, and having initial boiling point of substantially 245° C. is subjected to the action of hydrogen at 375° C. and 250 atmospheres pressure for such a length of time as to reduce sulphur content. The material of reduced sulphur content is then passed through a high pressure reaction chamber while simultaneously flowing hydrogen therewith at a temperature of 410° C. and 300 atmospheres pressure; the catalyst is molybdenum oxide and tin chloride and the flow of hydrogen so controlled as to induce no substantial percentage of coke or carbon in the reaction chamber, nor to induce any substantial percentage of chain structures that would preclude the provision of the solvent 40 of enhanced solvency of the present process.

Upon inspection the beneficiated coal tar fraction will be found to have a lowered specific gravity, coke residue, boiling range, viscosity and oxygen content, and, in the case of some fractional parts of the beneficiated material, a lowered solvency as compared to solvents extant.

The beneficiated material is stripped to 290° C. and the low boiling fractions thereof subjected to the action of hydrogen at 450° C. and 200 atmospheres pressure; flow of hydrogen 3,000 cubic feet per barrel feed and the time so controlled as to provide an increment of low boiling fractions in excess of fractional increment in the high boiling range. The solvency of the 55 finally processed material is in excess of the immediate starting material. The time of the last step may be a fractional minute, or more, as for instance several minutes.

The residue incidental to the stripping step 60 may be recycled or used as an article of commerce of enhanced value, as for instance binders or the like.

The starting material of high carbon content, as for instance coke oven tar is characterized by, 65 in its raw state, such a percentage of high molecular complexes or polymerized products that the refined solvents of the present invention are not possible of manufacture therefrom directly, but must be produced in step-wise manner, as heretofore explained, whereby among other things, the action of hydrogen depolymerizes said molecular complexes contained in the starting material.

The depolymerized or partially depolymerized tar or fraction thereof is then stripped of a percentage of its low ends whereby to provide the 75

intermediate parent material of the refined solvents of lowered corrosivity, said refined solvents characterized, as compared to the immediate starting material, by an increment of fractions in the lower boiling range in excess of fractional increment in the higher boiling range. The residue incidental to said stripping may, because of its depolymerized or partially depolymerized condition serves as recycle material to the end that conversion of the starting material in the percentage of the material finally remaining liquid approaches volume for volume of the starting material into the refined solvents of the present invention.

In the conversion of starting materials, partially or approaching unity, into the refined solvents of lowered corrosivity, temperatures as low as 300° C. may be employed; pressures as low as 50 atmospheres may be used. However, temperatures and pressures of an increased range provide better commercial practice. The time element is desirably that period which affords commercial recoveries of the product of, and incidental to, the present process. Temperatures are preferred that cause no substantial amount of coking.

Gas flows are usually held in excess of 3,000 cubic feet per barrel feed treated. In the step-wise application of hydrogen a few trials when using any of the starting materials will determine the gas flow when coordinated with the selected temperature and pressure conditions which effect said depolymerization. The gas flow in this instance may be a variable quantity because of the varying ranges of coordinated temperature and pressure that may be selected. When using a chosen coordination of temperature and pressure, a few trials will readily determine the gas flow that provides depolymerizing conditions to the end that solvency, specific gravity, viscosity, and boiling range are lowered.

Concerning the gas flow that increases solvency and provides an increment of low boiling fractions in excess of fractional increment in the high boiling range, said gas flow is held at that point which induces no percentage of finally liquid chain structures that will preclude the enhanced solvency of the present invention. For a given coordination of temperature and pressure, the gas flow in the last instance is lower than the gas flow in the preceding instance.

Using some starting materials a gas flow of 10,000-15,000 cubic feet per barrel feed, or higher, has proven satisfactory for depolymerizing conditions, and, a gas flow in the order of 6,000-8,000 cubic feet per barrel feed has proven satisfactory for the final hydrogen action, however, lower gas flows may be used.

Viewed broadly, the gas flow in the instance of depolymerizing conditions may be lower than 10,000 cubic feet per barrel feed, and the flow in the last instance is held at that point that increases solvency.

In the hydrogen action that reduces sulphur content, the action of hydrogen may be effected in an autoclave or in a continuous plant, and in the event of continuous practice, the gas flow is maintained so as to assist in sulphur reduction and the removal thereof from the reaction zone, the while inducing no substantial percentage of carbon or the like, nor percentages of liquid chain structures that would preclude the provision of the refined solvents of superior solvency of the present process.

Example 4.—It has been discovered that when subjecting certain mixtures of refined coal tar

fractions to the action of hydrogen in accordance with the present process for the production of solvents/or plasticizers the formerly accepted teaching that product increment, depolymerization and/or hydrogen absorption are linear functions of the time, is not followed.

When subjecting a mixture of crude coal tar fractions boiling predominantly above 250° C. or 275° C. to the action of hydrogen, research has disclosed that the newly induced products, depolymerization and/or hydrogen absorption are linear functions of the time. As an example, when the above mixture of crude tar fractions is subjected to the action of hydrogen for 2-, 5-, and 8-hour periods, the newly induced products, depolymerization and/or hydrogen absorption were linear functions of the time element.

One of the preferred starting materials of the present process is a mixture of refined coal tar fractions boiling predominantly above 355 or 380° C. Such a starting material is conveniently the final residue resulting from evaporating coal tar to dryness or substantial dryness and then stripping wood preservative from the distillate. This final residue mass of refined coal tar fractions is an especially suitable refined pitch to be used as starting material of the present process. However, in contradistinction to the mixture of crude coal tar fractions boiling predominantly above 250 or 300° C., when the aforementioned preferred starting material is subjected to the action of hydrogen for production of solvents and/or plasticizers, the newly induced fractions, depolymerization and/or hydrogen absorption are not, as described for the other mixture of crude tar fractions, linear functions of the time. A critical period of treatment by or with hydrogen exists, and which if exceeded causes loss of newly induced fractions, polymerization and/or lessened hydrogen absorption on certain fractions of the preferred starting material under treatment.

The critical time element because of the obvious possible variations in the characteristics of the aforementioned refined pitch cannot be spoken of as an arbitrary figure. It can be stated, however, that if the refined coal tar pitch were to be subjected to the action of hydrogen for such a length of time, which for other crude coal tar fractions would illustrate that the newly induced fractions, depolymerization and/or hydrogen absorption were linear functions of the time element, loss of induced products, polymerization and/or lessening of hydrogen absorption would occur. When treating the refined pitch by or with hydrogen, the critical time element is in the order of about three hours.

In the disclosures made herein and in the appended claims distillate removal of low boiling portions from the beneficiated material is considered the equivalent of fractional removal by gas movement, solvent action or the like. The converse also obtains.

A sulfur bearing refined coal tar pitch chosen from the group boiling predominantly above, and above, 355° C., characterized by content of oxygenated compounds, coke residue in excess of 2% and a specific gravity greater than 1 is subjected to the action of hydrogen at 385° C. and 200 atmospheres pressure whereby to lower sulfur content thereby lowering corrosivity, at least providing for lowered corrosivity in the finished product as hereinafter explained. The sulfur reducing hydrogen action is so controlled as to induce no substantial percentage of low boiling fractions, as for instance those low boiling frac-

tions whose ranges are disclosed elsewhere herein. The material of lowered sulfur content is then passed in liquid phase through a high pressure reaction vessel while simultaneously flowing hydrogen therewith in the presence of an oxide catalyst chosen from the group comprising the sixth and eighth periodic groups, and additional catalytic material adapted to influence the decomposition of oxygenated compounds contained in the starting material, at a temperature of 435° C. and 400 atmospheres pressure. The time of contact is two hours and the flow of gas 15,000 cubic feet per barrel material treated. The beneficiated refined pitch upon inspection will be found to have a lowered coke residue, boiling range, specific gravity, viscosity and oxygen content. Solvency in some of the lower fractions will be a reduced quantity as compared to the solvency of solvents extant of comparable boiling range.

The beneficiated refined pitch is stripped to an upper limit of 290° C. and the low boiling portion thereof is passed through a high pressure reactor with a flow of hydrogen at a temperature of 515° C. and 200 atmospheres pressure and for such a length of time as to increase solvency and produce an increment of fractions in the low boiling range in excess of fractional increment in the high boiling range, thus providing the refined solvent of superior solvency of the present process.

The residue resulting from the provision of the intermediate starting material may be recycled if desired for further solvent production. The residue is of a more liquid nature than a comparable cut on the starting material indicating that the high boiling ends which may be described as including multiplicity of ring structures has been, at least, either saturated or partially saturated, thus providing the initial step in the step-wise conversion of substantially the entirety of the refined pitch remaining liquid under process conditions into the refined solvents of lowered corrosivity of the present process.

In the instance of the immediate apparent material recovered to an upper limit of 290° C., as above described, the final solvent may be divided to provide solvents of various boiling ranges as may be dictated by necessity. When providing the intermediate starting material of the present process, and in the event such provision is made by taking a deep cut on the beneficiated refined pitch, the deep cut after further hydrogen action, as heretofore described, may provide high boiling fractions having plasticizing properties.

When subjecting a refined coal tar pitch to the action of hydrogen for the production of solvents in accordance with the present process, the hydrogen action characterized by solvency lowering is controllably held at or below the critical time period, and if such is exceeded adverse reactions will occur. As an example, if the critical time period is exceeded, instead of fractional increment, depolymerization and/or hydrogen absorption being linear functions of the time element, the reverse will obtain. In other words, if the critical time period is exceeded, fractional increment, depolymerization and/or hydrogen absorption will not be linear functions of the time element, it having been found, among other things, that a period in excess of that which is critical will provide for loss of fractional increment and/or polymerization.

As stated above the critical time element in the instance of treating the refined pitch with

hydrogen is in the order of about three hours, and the present process is predicated on the employment of the critical, and at times less than the critical, time element.

5 The refined solvents of lowered corrosivity as flowing from the conversion product of the refined pitch are of superior quality and are characterized by a preponderance of ring structures.

By the term *beneficiated* as used herein and in 10 the appended claims is meant the starting material at least once subjected to the action of hydrogen in accordance with the present process.

After the starting material has been subjected to depolymerizing action, the stripping step may 15 be effected at any point selected within a wide range to provide a cut capable of providing, after further processing, substitutes for the boiling range or ranges of benzol, toluol, xylol, the various naphthas, and the various plasticizers.

20 Thus, the depolymerized starting material may be cut according to the need at hand, said cut then being subjected to the action of hydrogen that increases solvency as heretofore explained.

In the step that effects depolymerization of the 25 high molecular complexes contained in the starting material, the inclusion of a catalyst adapted to influence the decomposition of oxygenated compounds contained therein, enhances said depolymerization and allows the reduction of specific gravity, viscosity, and coke residue to proceed at an enhanced rate.

The catalysts of the present process are oxides 30 and a material adapted to influence aforesaid decomposition of oxygenated compounds, said material being selected from the group consisting of halogens, halids and derivatives thereof including substitution and addition products thereof. Catalysts may be employed in any effective form as for instance as pellets, comminuted, or supported on carriers.

If desired, comminuted catalyst may be used in the hydrogen step characterized by depolymerization, and in the step characterized by solvency increase, a rigid catalyst may be used.

45 By multiplicity of rings, high molecular complexes and polymerized products are meant high boiling fractions of aromatic content a portion of which at least may be viewed as ring multiples: or, said terms, any or all, may be used to 50 describe high boiling fractions of the starting material especially susceptible to thermal degradation.

When subjecting high boiling fractions of the 55 starting materials to the process of the present invention, it may be desirable prior to the depolymerizing step, or the sulphur reducing step, to at least partially depolymerize the molecular complexes by use of a solvent. Said solvent may be added in a small amount, or up to volume for volume or more. Refractory solvents may be desirable, but others more susceptible to the reaction conditions inherent in and to the present process are usable.

Concerning solvents, it may be said that tar itself, as for instance, high temperature coke oven tar is constituted of high molecular complexes dissolved, cut back, or depolymerized with a solvent, said solvent being the lower boiling fractions of said tar.

70 The action of hydrogen may be effected in one or more cycles or chambers, with or without releasing the pressure and with or without variation of process controls.

Various modes of practicing the present invention are possible, as for instance the depoly-

merized starting material may be stripped by gas movement; the low ends thus stripped may then, with or without releasing pressure, be subjected to further action of hydrogen. Or, the desired stripped material may be obtained by partial release of pressure which would correspond to the fractional recovery desired or predetermined.

The process may be practiced in an autoclave and/or a single reaction chamber, a series thereof, a parallelism thereof, including a multiplicity thereof.

The refined solvent of the present invention may be fractioned to provide solvents and/or plasticizers of various boiling ranges, and in the instance where solvents are processed from a deep cut on the depolymerized material, the highest boiling fractions thereof or others may serve as a substitute for certain plasticizers.

In the first cycle of hydrogen action that reduces sulphur content, said reduction of sulphur may be accomplished in the presence of a catalyst. Catalysts effective in the presence of hydrogen are usable, as for instance the oxides and/or sulfides of molybdenum, vanadium, uranium, cobalt, tin, manganese, tungsten, or the like.

In the disclosure herein made the removing of low boiling fractions by gas movement or pressure release is considered the equivalent of distillation.

When reference is made to high molecular complexes contained in the starting material, and when the starting material contains low boiling fractions that are not considered high molecular complexes, it is of course obvious that the high molecular complexes contained in the starting material are to a certain extent depolymerized by the solvent present.

It will be seen that by reduction of sulphur content of the material under treatment during any stage of hydrogen action, the oxide catalyst used during subsequent stages is at least partially protected from the effect of the sulphur.

The decomposition influencer which it is desired to have present in the reaction zone is generally taken between 0.1 and 4 or 5 percent, based on the feed stock, and is preferably taken between 0.1 and 1.5 percent.

Halogens, halids and derivatives thereof are employed for catalytic purposes noted in the foregoing; however, also may be employed substances furnishing under the process conditions a halogen or a hydrogen halid. Ammonium chloride may be employed, also halogen compounds of coal tar oils, or the like as for instance the iodides or bromides. Also may be employed acids such as nitric, sulphuric, sulphonic, formic and acetic.

The addition of the decomposition influencer may be made prior to the entry of the feed stock into the reaction chamber, or at any suitable time, as for instance after the charging stock has been heated.

Equivalent amounts of compounds furnishing halogen or hydrogen halid may be employed.

The evaluation of solvent power is conveniently accomplished by finding the well-known aniline point of Kauri-butanol number. The evaluation of plasticizing properties is conveniently accomplished by recourse to methods suggested in chapter VI, "The technology of solvents," by Dr. Otto Jordon, Mannheim, Germany, translated by Alen D. Whitehead, Chemical Publishing Company of New York, Inc., New York, New York.

Minor changes may be made in the foregoing

without departing from the spirit of the invention.

I claim:

1. In the production of a solvent from the sulfur containing refined pitch produced by stripping high temperature coal tar to at least about substantial dryness, and fractionating the overhead material to recover a liquid useful as a wood preservative, and a higher boiling fraction boiling predominantly above 355° C., the process which comprises: subjecting said higher boiling fraction to the action of hydrogen at a temperature and pressure of at least about 375° C. and 50 atmospheres, respectively, and for such a time as to lower sulfur content, whilst precluding substantial low boiling fractional increment; subjecting the material of lowered sulfur content to the action of a relatively high flow of hydrogen at a temperature and pressure in excess of about 400° C. and 50 atmospheres, respectively, in the presence of an oxide catalyst and a material selected from the group consisting of halogens, halids and derivatives thereof for a period not in excess of about three hours, whereby to avoid loss of newly induced fractions; stripping newly induced fractions from the beneficiated material; and subjecting at least a portion of said stripped fractions to the action of a relatively low flow of hydrogen at a pressure of at least 50 atmospheres and a temperature chosen between 450-525° C. to provide an increment of fractions in the lower boiling range in excess of fractional increment in the higher boiling range, to produce a solvent.
2. In the production of a solvent from the sulfur containing refined pitch produced by stripping high temperature coal tar to at least about substantial dryness, and fractionating the overhead material to recover a liquid useful as a wood preservative, and a higher boiling fraction boiling predominantly above 355° C., the process which comprises: subjecting said higher boiling fraction to the action of hydrogen whereby to lower sulfur content, whilst precluding substantial low boiling fractional increment; subjecting the material of lowered sulfur content to the action of a relatively high flow of hydrogen in the presence of an oxide catalyst and a material selected from the group consisting of halogens, halids and derivatives thereof for a period not in excess of about three hours, whereby to avoid loss of newly induced fractions; stripping newly induced fractions from the beneficiated material; subjecting at least a portion of said stripped fractions to the action of a relatively low flow of hydrogen to provide an increment of fractions in the lower boiling range in excess of fractional increment in the higher boiling range; and fractionating the last named beneficiated material to segregate a solvent.
3. In the production of a solvent from the sulfur containing refined pitch produced by stripping high temperature coal tar to at least about substantial dryness, and fractionating the overhead material to recover a liquid useful as a wood preservative, and a higher boiling fraction boiling predominantly above 355° C., the process which comprises: subjecting said higher boiling fraction to the action of hydrogen whereby to lower sulfur content, whilst precluding substantial low boiling fractional increment; subjecting the material of lowered sulfur content to the action of a relatively high flow of hydrogen in the presence of an oxide catalyst and a material selected from the group consisting of halogens,

halids and derivatives thereof for a period not in excess of about three hours, whereby to avoid loss of newly induced fractions; stripping newly induced fractions from the beneficiated material; subjecting at least a portion of said stripped fractions to the action of a relatively low flow of hydrogen to provide an increment of fractions in the lower boiling range in excess of fractional increment in the higher boiling range; and fractionating the last named beneficiated material to provide a solvent boiling predominantly between 100° C. and 150° C.

4. In the production of a solvent from the sulfur containing refined pitch produced by stripping high temperature coal tar to at least about substantial dryness, and fractionating the overhead material to recover a liquid useful as a wood preservative, and a higher boiling fraction boiling predominantly above 355° C., the process which comprises: subjecting said higher boiling fraction to the action of hydrogen at a temperature and pressure of at least about 375° C. and 50 atmospheres, respectively, and for such a time as to lower sulfur content, whilst precluding substantial low boiling fractional increment; subjecting the material of lowered sulfur content to the action of a relatively high flow of hydrogen in the presence of an oxide catalyst and a material selected from the group consisting of halogens, halids and derivatives thereof at a pressure in excess of about 50 atmospheres and a temperature in excess of about 400° C. for a period not in excess of about three hours, whereby to avoid polymerization; stripping newly induced fractions from the beneficiated material; and subjecting at least a portion of said stripped fractions to the action of a relatively low flow of

hydrogen at a pressure of at least 50 atmospheres and a temperature chosen between 450-525° C. to provide an increment of fractions in the lower boiling range in excess of fractional increment in the higher boiling range, to produce a solvent.

5. In the production of a solvent from the sulfur containing refined pitch produced by stripping high temperature coal tar to at least about substantial dryness, and fractionating the overhead material to recover a liquid useful as a wood preservative, and a higher boiling fraction boiling predominantly above 355° C., the process which comprises: subjecting said higher boiling fraction to the action of hydrogen at a temperature and pressure of at least about 375° C. and 50 atmospheres, respectively, and for such a time as to lower sulfur content, whilst precluding substantial low boiling fractional increment; subjecting the material of lowered sulfur content to the action of a relatively high flow of hydrogen in the presence of a material selected from the group consisting of halogens, halids and derivatives thereof at a temperature and pressure in excess of about 400° C. and about 50 atmospheres, respectively, for a period not in excess of about three hours, whereby to avoid lowered hydrogen absorption; stripping newly induced fractions from the beneficiated material; and subjecting at least a portion of said stripped fractions to the action of a relatively low flow of hydrogen at a pressure of at least 50 atmospheres and a temperature chosen between 450-525° C. to provide an increment of fractions in the lower boiling range in excess of fractional increment in the higher boiling range, to produce a solvent.

JACQUELIN E. HARVEY, Jr.
